(No Model.)

H. A. MEYER.

MACHINE FOR WORKING RATTAN.

No. 293,343.

Patented Feb. 12, 1884.

UNITED STATES PATENT OFFICE.

HEINRICH ADOLPH MEYER, OF HAMBURG, PRUSSIA, GERMANY.

MACHINE FOR WORKING RATTAN.

SPECIFICATION forming part of Letters Patent No. 293,343, dated February 12, 1884.

Application filed May 12, 1883. (No model.) Patented in Germany June 6, 1882; in Belgium July 5, 1882, No. 53,390; and in Austria-Hungary October 19, 1882.

To all whom it may concern:

Be it known that I, HEINRICH ADOLPH MEYER, of Hamburg, in the Kingdom of Prussia, Germany, have invented certain new and useful Improvements in Machinery for Working Rattan, of which the following is a specification, reference being had to the accompanying drawings.

This invention consists in a machine of novel construction, whereby strips of chair-rattan are cut off from the outer skin of the cane-rattan completely ready for use without requiring further treatment on splitting or planing machines.

In the accompanying sheet of drawings, Figure 1 represents a side view, Fig. 2 a cross-section, and Figs. 3, 4, 5, and 6 details, of the machine, as will be hereinafter explained. Figs. 7 and 8 are transverse sectional views of the rattan.

The cane-rattan A, that has to be worked, is fed into and through the machine by rotating feeding-disks C C with hollowed out or grooved peripheries. These rotating disks act in conjunction with stationary pressers e e, to feed the rattan forward.

Directly near each presser e a cutter, s, is placed, that enters the surface or skin of the cane and cuts off a strip of size and shape required ready for use for chair-seats or other purposes. Each knife or cutter is furnished with a double cutting-edge, as shown in Figs. 6, 6^a, and 6^b, to separate two strips at same time, and it is kept in a holder or chuck, D, Figs. 3 and 4, which allows the strips cut off by the knife to escape through an opening, F, of the chuck. The chuck D is attached to a corresponding presser, e, and can, for the purpose of adjusting its knife s sidewise or in the direction of the axes of the feeding-disks C, be turned on bolt o by means of an adjusting screw, i, the end of which is ball-shaped, as shown in Figs. 3 and 5, and is placed in a recess of the top end of the holder D. After this adjustment of the knife the holder D is secured by a set-screw, z. (See Figs. 4 and 5.) The thickness of the strip cut off from the cane-rattan is regulated by a screw, h, which allows of lifting or lowering the pressure-foot e' of presser e. Presser e is, by means of springs m m', forced against

cane A, and moves up and down according to the changes of the thickness of the cane, thus preventing irregularities in the diameter of the cane or rattan from producing changes in the thickness of the strips cut off. By arranging two disks, C C, and corresponding pressers with knives or cutters on opposite sides of the cane passed through the machine opposite sides of the rattan can be acted upon simultaneously, and if the knives are double acting, as shown in Figs. 6, 6^a, and 6^b, four strips v, v', v², and v³, (see Fig. 7,) will be cut off at same time, after which the cane or rattan is turned ninety degrees and again passed through the machine, after which four more strips are cut off, leaving the core or pith, as shown in full lines by Fig. 8 of the drawings. This polygon-shaped cane or pith can be rounded off on machines not forming part of this invention, and only a very small loss of material results from this.

For enabling the knife or cutter to enter into the hard surface or skin of the cane the latter is, by means of small rollers t t, bent down to the circumference of the feeding-rollers C. The small rollers t are forced against the rattan by means of adjustable springs P, as is illustrated by the drawings, in one of the rollers t.

By the passage of the rattan around the rotating feeding-disks C C the knives or cutters are enabled to do their work more easily, as the strip or strips will take a rectilinear direction as they are cut off and delivered, while the body of the rattan will be deflected away from the back of the cutters and caused to follow the curvature of the said feeding-disks.

What I claim as my invention, and desire to secure by Letters Patent, is—

1. The combination of the rotary disk C, having a grooved periphery, the chuck D and its cutter s, the presser e and springs m m', for impelling it toward said disk, the bolt o, whereby said chuck is pivoted in said presser, and the screw i, for swinging the chuck D on said bolt o, and thus effecting the lateral adjustment of the cutter s relatively to said grooved disk, substantially as herein described.

2. The combination, with the disk C, chuck D, cutter s, and presser e, all arranged and operating substantially as herein described, of

the movable presser-foot e' , and the screw h , whereby it may be adjusted in the presser e relatively to the cutter s , as set forth.

3. The combination of the disk C , chuck D , cutter s , presser e , springs $m\bar{m}'$, movable presser-foot e' , rollers $t\bar{t}$, for holding the rattan against said disk in rear of and in advance of

the cutter s , and presser-foot e' , and springs P , all substantially as herein described.

HEINRICH ADOLPH MEYER.
